UNITED STATES PATENT OFFICE.

JOSEF BRAUTIGAM, OF DETROIT, MICHIGAN, ASSIGNEE, BY MESNE ASSIGNMENTS, OF ONE-HALF TO FRANK A. ROLF, OF DETROIT, MICHIGAN.

CARBURETER.

1,079,565.

Specification of Letters Patent.

Patented Sept. 9, 1913.

Application filed July 5, 1912. Serial No. 707,731.

To all whom it may concern:

Be it known that I, JOSEF BRAUTIGAM, a subject of the Emperor of Germany, residing at Detroit, in the county of Wayne and State of Michigan, have invented certain new and useful Improvements in Carbureters, of which the following is a specification, reference being had therein to the accompanying drawings.

10 This invention relates to improvements in carbureters especially adapted for use in supplying explosive charges to internal combustion engines and its object is to provide a simple construction which is such that a proper mixture of fuel and air will be provided at very low engine speed and which is so arranged that the mixture of air and fuel will be properly proportioned for all increased speeds and further to provide certain other new and useful features in the construction and arrangement of parts.

20 To these ends the invention consists in the matters hereinafter set forth and more particularly pointed out in the claims reference being had to the accompanying drawings in which—

Figure 1 is a central vertical section through a device embodying the invention; Fig. 2 a transverse section thereof showing 30 the air dome within the mixing chamber in elevation; and Fig. 3 is a transverse section substantially on the line 3—3 of Fig. 2.

In the drawing 1 represents a suitable float chamber into which fuel is admitted 35 by means of a valve 2 operated by a suitable float 3 to maintain a certain level of gasoline in the chamber. The construction and arrangement of the float and valve for controlling and maintaining a level of fuel in 40 the float chamber forms no part of this invention and any controlling means may be used.

A cylindrical casing 4 forms a mixing chamber 5 of the carbureter and the upper end of this casing is contracted to form a neck portion 6 which is flanged for attachment to an engine manifold or other distributor for the carbureted air passing from the mixing chamber. The usual throttle 45 valve 7 is pivoted within the neck portion of the casing upon a transverse pivot pin and is turned in any suitable manner as by means of a lever 8 secured upon the outer end of the pin. The lower end of the casing 4 is 50 closed by a bottom 9 having an axially

flanged opening 10 for the admission of air into the chamber. This bottom closure 9 is formed with a passage 11 extending longitudinally of a bridge bar 12 which extends across the opening 10 and this passage is 60 open at one end into the float chamber and at its opposite end communicates with a vertical passage 13 formed in the longitudinal axis of a nozzle member 14 which is screwed into an opening in the bridge bar 12 and extends vertically upward therefrom in the axis of the casing 4. The casing is removably secured to the bottom 9 which is preferably formed integral with the float chamber, by means of screws or bolts 15 passing 65 through openings in a flange on the casing.

Secured axially within the lower end of the casing 4, is an air dome 16 having a flange 17 at its lower end fitting within the lower end of the casing and secured to the bottom 9 by means of screws or bolts 18. This air dome is provided with an axial opening 19 in its top and the upper end of the dome is contracted slightly toward said opening into which the discharge end of the 70 nozzle 14 projects. The dome 16 is formed with a plurality of openings 20 along its base, said openings being preferably triangular in outline with the apex of the triangle cutting through the lower edge or base 75 of the dome.

Fitting loosely within the dome to slide vertically therein is a tubular valve member 21 which is formed with an axial opening 22 in its upper end of slightly greater diameter than the diameter of the nozzle 14 which is preferably tapered toward its upper or discharge end. The diameter of the lower end of the valve member is greater than the diameter of the air inlet opening 90 10 so that when said member is seated upon the bottom 9 it forms a closure for the air inlet and permits no air to pass into the casing except a small quantity which will be drawn in by the suction of the engine 100 through the small space between the edge of its opening 22 and the nozzle 14.

To raise the valve member 21 from its seat upon the bottom of the casing and permit air to pass beneath its lower edge 105 through the openings 20, said member is provided with a pair of arms 23 extending upward through openings in the top of the dome 16, and to the upper ends of these arms are pivotally attached links or rods 24 110

which in turn are pivotally connected to downwardly extending ears 25 on the throttle valve 7. When the throttle valve is opened by means of the lever 8, the valve member 21 will be lifted from its seat but if found desirable the valve member may be operated independently of the throttle valve in any suitable manner.

When the air valve 21 is seated and the air inlet choked thereby, air is drawn into the casing by suction of the engine, through the narrow space between the edge of the opening 22 in the valve member and the side of the nozzle which projects through said opening and thus a strong current of air is directed by the contracted upper end of said valve member upward around the discharge end of the nozzle to carry into the mixing chamber a large percentage of gasoline from the nozzle in proportion to the quantity of air admitted. The contracted upper end of the dome 16 also serves to direct the inrushing air upward around the nozzle and by reason of the strong suction which is created upon the nozzle by the valve and dome, a very small discharge opening may be provided in the nozzle from which the gasoline will be drawn in the form of a spray. The air drawn in in the initial starting of the engine is thus thoroughly carbureted and heavily charged with gasoline vapor thus making a very strong explosive mixture. The engine may therefore, be run at very low speeds by reason of a thorough carbureting of the air and the strength of the ingoing charges. As the speed of the engine is increased by the opening of the throttle 7, the valve member 21 will be lifted in proportion thereto and an increased supply of air will rush in beneath the lower edge of the valve member and through the openings 20 which are so shaped that the size of the opening through which the air may pass is increased both laterally and vertically as the member is raised. By reason of the tapering form of the upper end of the nozzle 14, the opening around said nozzle is also increased as the valve member is lifted and thus the suction upon the discharge end of the nozzle is reduced slightly as the speed of the engine increases. The proportion of air to fuel is thus increased as the speed of the engine increases, not only by the enlarging of the opening in the top of the valve member and consequent decrease of suction but also by the form of the openings 20 which is such that their capacity is multiplied as the valve is raised. In this construction the necessity for air and gasoline inlet adjustments is obviated as the valve member 21 operates to control both according to the requirements of the operation of the engine.

Obviously, changes may be made in the construction and arrangement of parts with-

out departing from the spirit of my invention and I do not wish to limit myself to the construction and arrangement shown.

Having thus fully described my invention what I claim is:—

1. In a carbureter, the combination with a casing having an air inlet, of concentric tubular members for controlling the air inlet having contracted adjacent ends each formed with an axial opening, a fuel supply member extending into the casing in the axis of said tubular members with its discharge end projecting through the axial opening in the inner of said tubular members and extending adjacent to the opening in the outer of said members, and means for moving one of said tubular members relatively to the other. 70

2. In a carbureter, the combination of a casing having an air inlet opening a fuel supply nozzle, a tubular controlling member surrounding the nozzle and adapted to seat at one end upon the casing around the air inlet opening and to be lifted from its seat to admit air to the casing beneath its lower end, said member being formed with a contracted upper end having an axial opening through which the nozzle discharges, and means for lifting said controlling member from its seat on the casing. 85

3. In a carbureter, the combination of a casing having an air inlet at its lower end and an axial discharge outlet at its upper end, a fuel supply nozzle extending upward in the casing at the axis of the lower end thereof, a tubular controlling member seating upon the bottom of the casing around said air inlet and formed with a contracted upper end having an axial opening of greater diameter than the diameter of the adjacent portion of the nozzle which projects therethrough, a member in the casing forming a vertical guide for the controlling member, and means for lifting the controlling member from its seat. 100

4. In a carbureter, the combination of a casing having an air inlet opening, a fuel supply nozzle extending into the casing at the axis thereof, a fixed tubular member in the casing around the air inlet opening and provided with openings near the end of the casing, a controlling member adapted to seat upon the casing around the air inlet and movable within the fixed member to open and close the said openings therein, said controlling member having a contracted end provided with an axial opening through which the nozzle projects, and means for moving the controlling member within the fixed member. 105

5. In a carbureter, the combination of a casing having an air inlet opening at its lower end, a dome within the casing surrounding the air inlet and provided with side openings and an axial outlet opening, a 110

tubular controlling member movable within the dome to control the flow of air through the side openings in the dome, a nozzle in the axis of the dome with its discharge end adjacent to said axial opening, and means for actuating the controlling member.

6. In a carbureter, the combination of a casing having an air inlet opening in its lower end and a discharge opening in its upper end, a fuel supply nozzle extending upward within the casing at the axis thereof, a fixed dome in the casing surrounding the air inlet opening and provided with openings in its side and an axial opening adjacent to the discharge end of the nozzle, a tubular controlling member slidable within the dome and adapted to seat upon the lower end of the casing around the air inlet opening, said controlling member being formed with a contracted upper end provided with an axial opening through which the nozzle extends, and means for lifting the controlling member from its seat.

7. In a carbureter, the combination of a cylindrical casing having an outlet opening in its upper end and provided with a bottom having an axial air inlet opening, a fuel supply nozzle extending upward in the casing at the axis of the lower end thereof and formed with a tapered discharge upper end, a fixed dome in the lower end of the casing having openings in its sides and an axial opening in its upper end adjacent to the discharge end of the nozzle, a tubular controlling member slidable within the dome and having a contracted upper end formed with

an axial opening of greater diameter than the diameter of the discharge end of the nozzle which projects therethrough, said controlling member being adapted to seat upon the bottom of the casing around the air inlet opening, and means for lifting the controlling member from its seat.

8. In a carbureter, the combination of a cylindrical casing having a contracted upper end forming an outlet, a bottom for the casing formed with an axial air inlet opening, a fuel supply nozzle extending upward from the bottom of the casing in the axis thereof and formed with a tapered upper discharge end, a fixed dome in the lower end of the casing surrounding the air inlet opening and provided with openings in its sides, and an axial opening in its top, a tubular controlling member adapted to seat upon the bottom of the casing around the air inlet opening to close the side openings in the dome and formed with a contracted upper end provided with an axial opening through which the tapering upper end of the nozzle projects, arms on the controlling member extending upward through openings in the dome, a throttle valve in the outlet to the casing, and means connecting the throttle valve and arm to lift the controlling member when the throttle valve is actuated.

In testimony whereof I affix my signature in presence of two witnesses.
